PHONOGRAPH

Orville M. Dunning, Glen Ridge, and Louis Z. La Forest, Orange, N. J., assignors to Thomas A. Edison, Incorporated, West Orange, N. J., a corporation of New Jersey

Application September 3, 1938, Serial No. 228,272

6 Claims. (Cl. 274—17)

This invention relates to phonographs, and more particularly to improved means for controlling the translating devices in phonographs of the type intended primarily for both the recordation and the reproduction of dictation.

A phonograph of the class mentioned comprises a record support, typically in the form of a mandrel, and a sound translating device mounted for movement along the record support and selectively adjustable into an inoperative condition and respective operative conditions for recording and reproducing. In a common form of sound translating device there are provided one or more elements movable into and out of record-engaging position as the device is adjusted into its operative and inoperative conditions. Such record engaging elements are of a delicate construction requiring careful handling in order to avoid damage being done thereto. In this and other similar arrangements wherein a record may be mounted on or removed from its support by a movement thereof relative to the translating device, serious damage may be done to the record and translating device if an attempt is made to mount the record on, or remove it from, its support whenever the sound translating device is adjusted into an operative condition.

It is an object of this invention to provide improved means in phonographs for avoiding such damage to the records and sound translating device.

Another object is to prevent damage to the record and to delicate parts of the machine by the provision of means automatically operated as an incident to an operation which the operator normally performs as he starts and stops dictation.

It is another object of this invention to provide, in phonographs, improved means for adjusting the sound translating device into operative and inoperative conditions as the phonograph driving means are rendered operative and inoperative.

It is another object of this invention to provide, in phonographs, a selector mechanism for the sound translating device and automatic means for adjusting the sound translating device in accordance with the setting of the selector mechanism.

It is a still further object to provide, in phonographs, power operated and manually controlled means for adjusting the sound translating device into its respective operative and inoperative conditions.

Other and allied objects will more fully appear

from the following description and the appended claims.

In the description of our invention reference is had to the accompanying drawings, of which:

5 Figure 1 is a top plan view of a phonograph in which a preferred form of our invention is incorporated;

10 Fig. 2 is a vertical cross-sectional view taken along the line 2—2 of Fig. 1 showing electrical means for adjusting the sound translating device, the translating device and a control lever therefor being shown in their respective inoperative positions;

15 Fig. 3 is a vertical cross sectional view of the carriage showing the sound translating device and the adjusting mechanism provided therefor in side elevation, the control lever for the sound translating device being in recording position;

20 Fig. 4 is a horizontal cross-sectional view of a portion of the mechanism of Fig. 3 taken substantially along the line 4—4 of Fig. 3, but showing the control lever and associated parts in inoperative position;

25 Fig. 5 is a diagrammatic view, partly in perspective, of mechanism and circuits in accordance with our invention.

Reference being had to Figs. 1 and 2, in particular, there will be seen a form of phonograph to which our invention is especially well adapted.

30 This phonograph comprises a base 1 having integrally formed therewith the left and right upright standards 2 and 3 and the intermediate standard 4. There is journaled in the standard

4 a shaft 5 bearing a record support or mandrel 6 which removably carries a cylindrical record

35 7. The mandrel 6 is preferably of a form comprising a tapered cylinder having a contractile and expandable chuck 8 at its open or rightward end which is adapted to be operated by imparting axial movement to a handpiece 8'; such a mandrel is disclosed in Gramann Patent No. 2,010,717, issued on August 6, 1935, and entitled "Phonograph." The left and right standards 2 and 3 support forward and rearward longitudinal rods

40 9 and 10 on which a carriage 11 is slidably mounted for movement along the record 7. The carriage has a forwardly extending arm 11' supporting a sound translating device 12 which, in its usual

45 form, is selectively adjustable for sound recording and sound reproducing. For conducting the sound waves to and from the sound translating device 12 there is provided a flexible tube 13 carrying, at its far end, a handpiece 13' usable as a mouthpiece for recording, and as an earpiece

50 for reproducing. On the handpiece 13' there

may be conveniently located a hand switch 14 for controlling the operation of the phonograph.

The handpiece 13' is adapted to be supported during the non-use of the phonograph by a forwardly extending arm 15 having a hooked forward portion fitting the handpiece. The arm 15 is pivotally mounted on the base plate 1 in the front left-end section thereof, wherein there is provided an inclined raised portion 1', carrying a pivot screw 15' about which the arm 15 is pivoted and having a suitable opening through which the arm 15 extends. The arm 15 is resiliently maintained in an upward position, as shown in Fig. 2, and is arranged to swing downwardly when the handpiece 13' is placed thereon to operate a switch 16 serially connected in a power circuit 17, which circuit is connected to the phonograph with a suitable power source by way of a plug 17', as schematically shown in Fig. 5.

During operation of the machine, the carriage 11 is moved steadily along the record 7 longitudinally thereof by means of a feed screw 18 journalled in the left and right standards 2 and 3 and coupled to the shaft 5 by a train of gears 19. On the carriage 11 there is provided a feed nut 20 which is arranged to couple the carriage to the feed screw 18. The feed nut 20 may be aptly located in the rearward hollow portion of the carriage 11 and may be secured to a bracket 21 pivotally connected to the carriage by a pin or rod 22 supported by the side walls of the carriage. In order that the carriage 11 may be readily disconnected from the feed screw 18 and be manually movable along the mandrel at will, there is provided on the bracket 21 a forwardly extending arm 23 having a cam face 23' coacting with a lateral pin 24 provided on the hub 25 of a control lever 26. The control lever 26 is pivotally mounted on a carriage sleeve 9' embracing the rod 9, the control lever extending upwardly through a slot 27 in the carriage. When the lever 26 is in its central or neutral position the bracket 21 is maintained in its most counterclockwise position by the coaction of the cam face 23' with the pin 24, the feed nut 20 then being free of the feed screw 18. Forward and rearward rocking movements of the control lever 26 from its neutral position, however, act to free the pin 24 of the cam face 23' so that the bracket 21 may turn in a clockwise direction, as by reason of a tension spring 28, to bring the feed nut 20 into engagement with the feed screw 18.

The mandrel 6 is rotated by a motor M, shown schematically in Fig. 5, which may be coupled as by a belt to a pulley 29. This pulley is rotatably mounted on the inner side of the standard 2 and is axially in line with the shaft 5 to which it is adapted to be connected by a clutch. This clutch may comprise a toothed member 30 secured to the pulley 29, and another toothed member 31 splined to the shaft 5 for movement into and out of engagement with the member 30. Such movement of the member 31 may be effected by imparting a rocking movement to a lever 33 pivotally mounted on a bracket 34 secured to the standard 4 by the screws 35. The lever 33 carries a pin 36 engaging an annular groove 32 provided in the clutch member 31, and extends downwardly therefrom beneath the base plate 1 to make connection with suitable actuating means, this means being preferably of the form described in Langley Patent No. 1,380,486, issued June 7, 1921, and entitled "Controlling device."

A clutch-actuating mechanism 37 of the afore-

mentioned type is shown diagrammatically in Fig. 1 and comprises two sets of electromagnets 38 and 38' operating the armatures 39 and 39', of which the armature 39' is coupled to the lever 33 by the link 33'. As appears in the mentioned Langley patent, when a circuit is established to cause current to flow through one set of electromagnets, both armatures are swung in the direction of that set to operate the clutch. When the armatures have substantially reached their terminal positions in that movement, a suitable switch is operated to break the circuit of the set of electromagnets through which current has been passing and to prepare the circuit of the other set of electromagnets for operation. When the other set of electromagnets is energized, the reverse operation takes place, the clutch being shifted to its other position, the circuit through the last mentioned set of electromagnets being broken, and the circuit of the first set of electromagnets being again prepared for operation.

In Fig. 5 there is shown the circuit diagram of the phonograph control circuits, including the electrical circuits incorporated in the herein disclosed embodiment of our invention. From this diagram it will be seen that the switch 16 controls the power supply to all of the power-operated mechanisms of the phonograph, and that the operation of the motor M is fully controlled by this switch. When the handpiece 13' is resting on the arm 15, the switch 16 is opened to disconnect the phonograph from its power source; but when the handpiece 13' is removed from the arm 15, as when the phonograph is to be put into use, the switch 16 is closed to put the motor M in operation and to render the other power-operated mechanisms operative. The pulley 29, which is coupled to the motor M, thus moves continuously during the use of the phonograph.

The switch 14 on the handpiece 13' is arranged to control the clutch-actuating mechanism 37 shown diagrammatically in a simplified form in Fig. 5. The switch 14 is of the single-pole two-way type comprising a pole member 39 and the contact members 40 and 41. The switch has a base portion integral with the handpiece 13', and a relatively movable portion or cover 42 secured to the handpiece by a pivot screw 43, as shown in Fig. 1. The cover 42 is preferably resiliently maintained in its upward position in any convenient manner, as by an upward bias of the pole member 39; in this position the pole member 39 makes electrical connection with the contact member 40. As the cover 42 is moved downwardly the pole member 39 breaks contact with the contact member 40 and thereafter makes contact with the contact member 41.

The switch 14 is suitably connected to the actuating mechanism 37 by means of a three-wire cable 44 extending along and within the flexible tube 13 to the sound translating device 12, at which point the cable is suitably extended onwardly within a flexible protective casing 45 to the actuating mechanism 37. The cable 44 is connected so that the contact members 40 and 41 are associated with the respective sets of electromagnets 38' and 38 of the mechanism 37. When the cover 42 of the switch 14 is resting in its outward position, with the pole member 39 making connection with the contact member 40, the clutch is adapted to be in disengaged position, the circuit of the electromagnets 38' then being open so that no current will pass through the mechanism 37. But as the switch 14 is operated

to make connection between the pole member 39 and the contact member 41, current will pass momentarily through the electromagnets 38 so as to operate the mechanism 37 to engage the clutch. When the switch is again operated to make connection between the pole member 39 and the contact member 40, current will pass momentarily through the electromagnets 38' to operate the mechanism 37' to disengage the clutch. The rotation of the record and the movement of the translating device along the record for recording thereon or reproducing therefrom are thus readily controlled by the hand switch 14.

The sound translating device 12, which is well known in the art, comprises an inverted cup member 46 (see Fig. 3) provided with an upwardly extending neck 46' to which may be suitably connected the flexible speaking tube 13. The member 46 has also a downwardly extending lug 47 which carries a cross pin 48 having conical end portions forming pivots for a pair of angular spring arms 49 attached to a sound box 50 disposed substantially concentrically with the cup member 46. The sound box 50 carries a stirrup 51 bearing a recorder stylus 52. The sound chamber of the sound box 50 communicates with the neck 46' by means of a tube 53 which forms a universal joint with an apertured dome 50' of the sound box 50. By this arrangement any swinging movement of the sound box 50 is caused to be accompanied by a sliding movement of the tube 53 within the neck 46', the sound box 50 being thus maintained in communication with the speaking tube 13 throughout such swinging movement.

The translating device 12 is also provided with a biasing weight 54 which is normally used only during the operation of reproducing. This weight is disposed between the sound box 50 and the record 7 and is pivotally secured to an arm 55 by means of a shoulder screw 56, the arm 55 being pivotally mounted on the cross pin 48. The weight 54 is thus free to swing in a transverse direction about the screw 56 and in a vertical direction about the pin 48. The weight 54 is suitably apertured to permit the stirrup 51 and the stylus 52 to extend freely therethrough during the recording operation. The weight 54 carries a cross-pin 58 on which is pivoted an angular stylus lever 57, shown in Fig. 3. The outer or lower end 57' carries a reproducing stylus 59 and the inner end 57'' is positioned within the stirrup 51 at all times.

In the adjustment of the translating device 12 for recording, both the sound box 50 and the weight 54 are permitted to move downwardly, the weight 54 moving to a position in which it may be suitably supported by the record 7, and in which it plays no part in recording, and the sound box 50 moving downwardly until the recorder stylus 52 engages the record 7. As so adjusted, sound waves conducted into the chamber of the sound box 50, by way of the speaking tube 13, will actuate the recorder stylus 52 to form on the record, as the record 7 is rotated and the carriage 11 is moved steadily forwardly therealong, a continuous groove having modulations in accordance with the sound waves.

In the adjustment of the translating device 12 for reproducing, the sound box 50 is moved into an upward position wherein the recorder stylus 52 is free of the record 7 and the weight 54 is left in a free floating condition. The rearward end 57'' of the stylus lever 57, which lies

within the stirrup 51, is thus also moved upwardly with the latter. The weight 54, being in a free floating condition, urges the reproducer stylus lever 57 downwardly so as to bias the reproducer stylus 59 against the record 7. The weight 54 moreover provides sufficient inertia so that vibrations imparted to the reproducer stylus 59, as it tracks a modulated groove of a rotating record, are almost wholly transmitted to the sound box 50. Sound waves will thus be created within the sound box 50, in accordance with the modulations of the groove being tracked, and these waves will be conducted outwardly by way of the tube 13.

In the adjustment of the translating device 12 to inoperative condition both the sound box 50 and biasing weight 54 are moved upwardly to free the styli 52 and 57 of the record supported by the mandrel 6, as shown in Fig. 2. It is only when the translating device 12 is so adjusted that a record may be safely mounted on, or removed from, the mandrel 6. Heretofore it has been customary to adjust the translating device by means of the control lever 26, this adjustment being arranged so that recording and reproducing adjustments are effected when the control lever 26 is in its respective forward and rearward positions, and so that a neutral or inoperative adjustment is effected when the lever is in its neutral or central position. In this known arrangement there was no protective means for preventing the operator from accidentally manipulating the record with respect to the mandrel 6 while the translating device was adjusted in an operative condition. The record and translating device were thus subjected to the hazard of being damaged. As a protective means against such hazard it has been customary to partially obstruct the free mounting of a record on the mandrel, or its removal therefrom, whenever the translating device is adjusted in an operative condition. This operation has not been altogether satisfactory, since it does not guard the mandrel sufficiently to prevent the operation of its ejecting mechanism, the operator being thus permitted to at least partially remove a record from the mandrel while the translating device is adjusted in an operative condition.

In our invention we provide means for automatically adjusting a sound translating device into operative and inoperative conditions, as an incident of putting the phonograph into and out of operation. This adjusting means may, for example, be responsive to—i. e., called into play by the manipulation of—the means controlling the record rotation and/or the carriage movement, such means being in the present instance the switch 14. This adjusting means may be operated in various suitable ways, such as by the power means of the phonograph or by a separate actuating mechanism. Whenever the sound translating device is of a combined form adapted for both recording and reproducing, we provide a manually or otherwise operable selector mechanism which is adapted to limit and control the function of the adjusting means. This selector mechanism is preferably provided with an inoperative or neutral position and an operative position for each function of the translating device. When the selector mechanism is in neutral position the translating device is rendered inoperative; however, when the selector mechanism is set in an operative position, the translating device is adjustable, as by the automatic adjusting means provided therefor, between in-

operative condition and that operative condition which corresponds to the setting of the selector mechanism.

In Figs. 1, 2, 3 and 4 there is shown an embodiment of our invention comprising a selector mechanism controlled by the manually operable lever 26, and an actuating mechanism 60 for adjusting, or shifting the adjustment of, the translating device in accordance with the setting of the selector mechanism. In this arrangement the translating device 12 is adjusted to its various positions by the suitable operation of a pair of angular lifting arms 61 and 62 fulcrumed on the rod 22 and arranged to engage with respective lifting tabs 50" and 54" on the sound box 50 and the biasing weight 54. The arm 61, controlling the sound box 50, is extended upwardly from its pivoting axis and there connected with a tension spring 63, the spring 63 making connection at its other end with a rod 63' on the carriage, so as to bias the arm 61 in an upward direction. The control lever 26 controls the movement of the arm 61 through a cam 64 on the arm 61 and the pin 24 on the hub of the control lever 26. This cam is arranged to maintain the arm 61 in its most downward position when the control lever 26 is in its forward or recording position. As the control lever 26 is returned to neutral or inoperative position, the arm 61 is moved in an upward direction, as by the force of the spring 63, to place the sound box 50 substantially in its most upward position when the control lever 26 reaches neutral position. As the control lever is moved into its most rearward or reproducing position, the pin 24 moves past a detent 64' on the arm 61, which serves to yieldably retain the control lever in its reproducing position; the arm 61 is, however, retained by the spring 63 in an upward position wherein to effect an upward biasing of the sound box 50 against the frame 46 of the translating device.

The arm 62, controlling the biasing weight 54, is mechanically free of the control lever 26 and is operated by the actuating mechanism 60 controlled by the hand switch 14, such control being, however, restricted by the control lever 26, as is hereinafter explained. The actuating mechanism 60 (see Figs. 2 and 3) is in all respects similar to the actuating mechanism 31 and comprises two sets of electromagnets 65 and 65' having the respective cores 66 and 66' and operating the pivoted armatures 67 and 67'. The armatures 67 and 67' are respectively provided with coacting cam portions 67a and 67a' resiliently maintained in engagement by a tension spring 68. In operation, the armatures are alternately actuated, the cam portions 67a and 67a' being adapted so that the unactuated armature remains locked in position until the actuated armature reaches the end portion of its travel. At this time the lock on the unactuated armature is removed and this armature then moves by the force of the spring 68 toward the other into a position for subsequent actuation. Such movement of the unactuated armature serves to lock the armature last actuated. When the electromagnets corresponding to the armature unactuated in the last operation, are now energized the reverse process takes place.

Interposed between the armatures 67 and 67' is an insulatedly and pivotally mounted arm 69 carrying a vibration and sound absorbing pad 70, commonly made of felt. The arm 69 is connected with a switch arm 71 serving as a pole member for alternately making connection with

5 a pair of contact members 72 and 72'. As the armatures are alternately actuated the switch arm 71 remains in position until the unactuated armature moves, the switch arm 71 then being 10 rocked to its other position. When the mechanism 60 is in the position shown in Fig. 2, the armature 67 having been last actuated, the switch arm 71 makes connection with the contact member 72' which is connected with one side of the electromagnets 65', the contact member 72 being connected with the electromagnets 65, as shown in Fig. 5. If the electromagnets 65' are then energized by way of a circuit including the contact member 72' and the switch arm 71, the armature 67' will move to its rightward position (see Fig. 2) and then the armature 67 will move rightwardly and thereby break the circuit of the electromagnets 65'. If the electromagnets 65 are then energized by way of a circuit including the contact member 72 and switch arm 71, the reverse operation takes place, the armature 67 moving to its leftward position and the armature 67' then moving leftwardly to break the circuit of the electromagnets 65.

25 In order that the mechanism 60 may be properly controlled by the hand switch 14 the sets of electromagnets 65 and 65' are connected, on the sides opposite to those making connection with the contact members 72 and 72', to the respective contact members 40 and 41 of the hand switch, and the switch arm 71 is connected to the power source on the side opposite to that making connection with the pole member 39 of the hand switch 14. By this arrangement the armatures 67 and 67' are caused to be in their respective leftward positions, as shown in Fig. 2, when the switch 14 is in its normally outward position with the pole member 39 making connection with contact member 40, and the armatures 67 and 67' are caused to be in their respective rightward positions when the switch 14 is thrown to its other position.

30 The armature 67 is connected to the lifting arm 62 by means of a link member 73. This member is suitably connected to the arm 62 by a stud 74 secured to the arm 62, extending rightwardly of the carriage through an opening 74' and pivotally connected to the member 73 by means of a shoulder screw 73'. The link member is also pivotally connected to the armature 67 by a shoulder screw 75, and is of a length such that the lifting arm 62 will be in its upward position when the armature 67 is in its leftward position, as shown in Fig. 2. The biasing weight 54, controlled by the arm 62, is then maintained 35 in its upward position, and consequently the sound box 50, disposed directly above the biasing weight, is then necessarily in its upward position. When the actuating mechanism 60 is operated so that the armature 67 is moved rightwardly, the lifting arm 62 moves downwardly to permit a free downward movement of the biasing weight 54 into a position wherein it is supported by the record. With this arrangement there 40 may be desirably provided means for locking the control lever 26 against movement from one position to another while the translating device is in an operative condition. Such locking means may comprise an upward extension 62' on the arm 62, which engages with the teeth 62" on the hub 25 of the control lever 26 when the arm is in a downward position. The operation of the adjusting mechanism of the translating device 12 is thus as follows:

45 With the control lever 26 in recording position.

as shown in Fig. 3, the translating device may be adjusted between inoperative and recording conditions. The arm 61 is then in its downward position, permitting free downward movement of the sound box 50 until the recorder stylus 52 engages the record. With the hand switch 14 in normal inoperative position, as shown in Fig. 1, the armature 67 is in its leftward position, the arm 62 being then in its upward position, and the biasing weight 54 and sound box 50 therefore being in an upward or inoperative position. When the switch 14 is operated downwardly to start rotation of the record and forward movement of the carriage, the mechanism 60 is operated to bring the arm 62 into a downward position. The weight 54 and sound box 50 may then move downwardly into suitable positions for recording. When the switch 14 is again operated to stop the movement of the carriage and the rotation of the record, the mechanism 60 is operated to move the weight 54 and sound box 50 into inoperative positions.

When the control lever 26 is in its rearward or reproducing position, the translating device may be adjusted between inoperative and reproducing conditions. The arm 61 is then in its upward position for supporting the sound box 50 in the position in which it is adapted to be located for reproducing; whereas the arm 62 is again operated between upward and downward positions, as the switch 14 is operated to start and stop movements of the record and carriage, for respectively adjusting the translating device into its inoperative and reproducing conditions.

In order to insure that the translating device will be maintained in inoperative condition when the control lever 26 is in neutral position, the actuating mechanism 60 is rendered inoperative to move the lifting arm 62 downwardly while the control lever 26 is in such neutral position. This inoperation of the mechanism 60 is effected by means of a switch 76, shown in Fig. 1, which is serially connected in the circuit of the electromagnets 65', this switch being open when the control lever 26 is in neutral position. The switch 76 comprises a pair of normally open contact arms 77 and 78 which are insulatedly supported preferably in a molded frame 79 resting on the carriage 11. Pivotally secured to the control lever 26, intermediately thereof, is a bar 80 having a longitudinal slot 81 through which passes a shoulder screw 82 threading into the frame 79. The bar is thus adapted to slide forwardly and rearwardly as the control lever 26 is moved into recording and reproducing positions. Insulatedly connected to the bar 80 is a pin 83 slidably contacting a cam portion 77' of the adjacent contact arm 77 for moving the arm rightwardly into contact with the arm 78, as the control lever 26 is operated from neutral position to either recording or reproducing position. The mechanism 60 is thus fully operable when the control lever 26 is in recording and reproducing positions but it is restricted so that it cannot shift the translating device from an inoperative condition to an operative condition when the control lever 26 is in neutral position, the mechanism 60 being, however, operative to shift the translating device from an operative condition to an inoperative condition when the control 26 is in such neutral position.

Although we have shown and described our invention in terms of a certain embodiment, it will be understood that many modifications and changes may be made therein without depart-

ing from the scope of our invention, which we undertake to express according to the following claims.

We claim:

5. 1. In a phonograph having record rotating means: in combination, means for controlling said record-rotating means; a sound translating device adjustable from an inoperative condition into respective operative conditions for recording and reproducing; a manually controllable selector mechanism for said translating device having at least recording and reproducing settings; means, responsive to the means controlling said record-rotating means, for effecting adjustment of said translating device between inoperative condition and the operative condition corresponding to the setting of said selector mechanism; and means for locking said selector mechanism against movement from one setting to another while said record-rotating means is in operation.
10. 2. In a phonograph: in combination, a sound translating device adjustable between an inoperative condition and respective operative conditions for recording and reproducing; selector means for said translating device, characterized by a neutral position and respective operative positions for recording and reproducing; means, operable when said selector means is in an operative position, for adjusting said translating device between inoperative condition and the operative condition corresponding to the setting of said selector means; and means, influencing said adjusting means while said selector means is in neutral position, for restricting the adjustment of said translating device from operative to inoperative conditions only.
15. 3. In a phonograph including record-support rotating means: the combination of control means controlling said record-support rotating means and operable either to render the latter operative or inoperative; a translating device and means associated therewith for adjusting it, in relation to a record on said support, either into inoperative condition or respective operative conditions for recording and reproducing; and an operative connection between said control means and said adjusting means and effective when the control means is in position to render the record-support rotating means operative, for rendering said adjusting means inoperative.
20. 4. In a phonograph having means for rotating a record and means associated with the latter for controlling the same: the combination of a translating device and means cooperating therewith to adjust it in relation to the record into operative and inoperative conditions; means, connecting said record-controlling means with said adjusting means, for causing said translating device to be adjusted into operative and inoperative conditions upon the starting and stopping of record rotation; manually operable means selectively movable either to render said adjusting means effective or to maintain said translating device in inoperative condition; and means operatively connected with said adjusting means and rendered effective in the actuation of the same to place said translating device into operative condition, for locking said manual means.
25. 5. In a phonograph having record-support rotating means: the combination of control means associated with said record-support rotating means for rendering the latter operative and inoperative; a translating device adjustable in

relation to a supported record into operative and inoperative conditions; means, controlled by said control means, for adjusting said translating device into operative and inoperative conditions; and means operatively associated with said adjusting means and controllable to restrict the operation of the same to render it effective to adjust said translating device from operative to inoperative conditions only.

6. In a phonograph including record-support rotating means: the combination of control means controlling said record-support rotating means and operable either to render the latter operative or inoperative; a translating device and a mechanism associated therewith for adjusting it, in relation to a record on said support, either into inoperative condition or respec-

5 tive operative conditions for recording and reproducing, said adjusting mechanism including means to shift said device between operative and inoperative conditions and selector means movable from a neutral position into recording and reproducing positions to select the operative condition effected by said shifting means; means to lock said selector means while said shifting means is in operative position; and means, rendered effective by said selector means in the movement thereof into neutral position, for restricting actuation of said shifting means to movement from operative to inoperative positions only.
